Fig. 4.

Fig. 5.

Fig. 6.

FIG. 1 is a front elevational view of a sitz bath embodying my new design;

FIG. 2 is a side elevational view thereof, the opposite side being substantially the same;

FIG. 3 is a rear elevational view thereof;

FIG. 4 is a top plan view thereof;

FIG. 5 is a bottom plan view thereof shown broken away for convenience of illustration; and

FIG. 6 is a sectional view taken on line 6-6 of FIG. 4 and looking in the direction of the arrows.

The stippling in the several views represents contrasting areas.

I claim:

The ornamental design for a sitz bath, as shown and described.
